(57) CLAIM

The ornamental design for a bed sheet with pockets as shown and described.

DESCRIPTION

FIG. 1 is a left, front and top perspective view of a bed sheet with pockets showing my new design;

FIG. 2 is a right, rear and bottom perspective view thereof;

FIG. 3 is a front elevational view thereof;

FIG. 4 is a rear elevational view thereof;

FIG. 5 is a right view thereof;

FIG. 6 is a left view thereof;

FIG. 7 is a top plan view thereof;

FIG. 8 is a bottom plan view thereof; and,

FIG. 9 is an enlarged view of a portion labeled as 9 on FIG. 1.

The long dash-short dash broken lines depict enlargement boundaries that form no part of the claim. The evenly broken lines illustrate portions of the article that form no part of the claimed design.

1 Claim, 9 Drawing Sheets
